CLAIM

The ornamental design for a LED wall pack light, as shown and described.

DESCRIPTION

FIG. 1 is a front view of a LED wall pack light of the present invention.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a top left perspective view thereof; and,

FIG. 8 is a bottom right perspective view thereof.

The broken line disclosure represents portions of the light which form no part of the claimed design.
